E. L. DELANY

HINGE FOR THE SEATS AND COVERS FOR TOILETS

Filed Feb. 5, 1925

FIG. 1.

FIG. 2.

FIG. 3.

Inventor

E. L. Delany.

By

C. R. Wright, Jr. Attorney

UNITED STATES PATENT OFFICE.

EDWARD L. DELANY, OF BROOKLYN, NEW YORK, ASSIGNOR TO DELANY REALTY CORPORATION, OF BROOKLYN, NEW YORK.

HINGE FOR THE SEATS AND COVERS FOR TOILETS.

Application filed February 5, 1925. Serial No. 7,973.

My invention relates to improvements in hinges for the seats and covers for toilets.

The object of my invention is to provide a hinge adapted for this purpose in which the pivotal carrying member of the cover is rigidly held by the seat against rotation, and whereby the pivotal carrying member is positively carried upwardly when raising the seat, carrying with it the cover.

Another object of my invention is to provide a hinge of this character in which the pivotal carrying member for the cover is firmly locked in the seat against lateral movement, and also forming trunnions, whereby the same may be rotatably mounted in studs carried by the hopper.

A further object of my invention is to provide a simple, cheap and effective device of this character having certain details of structure and combination of parts hereinafter more fully set forth.

In the accompanying drawings:

Figure 1 is a top plan view of a toilet seat showing my improved hinge applied thereto.

Figure 2 is an enlarged side elevation of Figure 1 showing the seat and cover partly broken away.

Figure 3 is a vertical transverse sectional view taken on the line 3-3 of Figure 2, and showing the studs attached to the hopper.

Referring now to the drawings, 1 represents the hopper which, in the form shown, is provided at each side with the outwardly extending flanges 2 provided with openings 3 through which the threaded portions 4 of the studs 5 pass. The studs 5 as shown, are screw-threaded and are clamped to the hopper by means of the nuts 6, screwed thereon below the flanges 2. While I have shown this specific attaching means for the studs 5, it will be understood that the same can be readily varied to suit hoppers of different characters and therefore I do not care to limit myself to any specific means of attaching the studs to the hopper.

The body of the hinge comprises the L-shaped plate 7, the upper end of which is provided with the inwardly extending stud 8, loosely passing into an opening 9, carried by the cover 10. The horizontal portion 11 of the L-shaped member 7 is provided on its inner face with an inwardly extending squared lug 12 tightly fitting into corre-

spondingly shaped openings 13 in the seat 14. This squared portion 12 is provided with an internally screw threaded recess 15, while the other plate 17 has the squared member 16 provided with an opening extending entirely therethrough and through the L-shaped hinge member 7. The outer face of the L-shaped hinge member 7, opposite the squared member 12 is provided with a trunnion 18 adapted to rotate within the recess 19 in the inner face of the stud 5. The L-shaped member 17 opposite the squared member 12 is perfectly flat and passing through the opening 16 therein, is a rod 20 having a screw threaded inner end 21 adapted to screw into the internally threaded recess 15.

The outer end of the rod 20 is screw threaded as indicated at 22 and upon which is screwed the trunnion 23, which is adapted to enter the recess in the stud 5, and adapted to freely rotate therein. The trunnion 23 is provided with a kerf 24, whereby the trunnion may be screwed upon the end of the rod 20 by means of a screw driver or a light tool. The member 17, at its upper end is provided with a stud 25 entering the recess 26 in the cover 10.

From the foregoing description it will be seen that the two L-shaped hinge body portions 7 and 17 are firmly clamped to the seat 14 and held against movement, and prevented from spreading by means of the trunnion 23, screwed on the rod 20 and thus assume their proper vertical alignment so that the cover is held between the upper ends thereof and free to rotate on the studs 8 and 25. This construction also provides a very simple and effective means of assembling the seat and cover and has many marked advantages over the old style seat and cover in which both the seat and the cover rotate independent of each other on the hinge member connecting the seat and cover.

Having thus fully described my invention what I claim is:

1. In combination with a toilet, of two studs carried thereby, a seat, two plates removably carried by the seat and rigidly connected thereto, an integral trunnion carried by one of the plates, a bolt passing through the seat and screwed into one of the plates, a trunnion carried by the bolt on the outside

of the other plate, and a cover pivotally mounted between the upper ends of the plate.

2. In combination with a toilet, a seat, a plate secured to one edge of the seat and having an inwardly extending rectangular projection entering the seat and having a screw threaded recess therein, a plate having a rectangular projection on its inner face entering the opposite edge of the seat, and an opening therethrough, a rod passing through said opening and through the seat, and screwed into the threaded recess of the other plate, a trunnion screwed on the rod on the outside of the plate, a rigid trunnion carried by the other plate, and studs carried by the toilet and having recesses to receive said trunnions, and a cover pivotally mounted between the ends of the plate.

3. In combination with a toilet, of studs rigidly carried thereby and having recesses in their faces, a seat, a plate having a rectangular projection on its inner face entering a correspondingly shaped recess in the seat, a trunnion carried by the outside of the plate and entering the recess of one of the studs, a plate having an inwardly extending rectangular lug entering a correspondingly shaped recess in the seat, a bolt loosely passing through the plate and lug and screw threaded into the rectangular lug of the other plate, a trunnion screwed on the rod on the outside of the plate, and a cover pivotally mounted between the upper ends of the plates.

4. In combination with a toilet, of two studs rigidly carried thereby, and having recesses in their inner faces, a seat, a plate on each side of the seat, and having inwardly extending rectangular lugs entering correspondingly shaped recesses in the seat, a rod

extending through one of the plates and entering a threaded recess in the other plate and drawing the plates together, trunnions carried by the outer faces of the plates and 45 entering the recesses in the studs, and inwardly extending projections carried by the upper end of the plates and entering recesses in the cover for pivotally supporting the same.

5. In combination with a toilet, of two studs carried thereby, and having recesses on their inner faces, a seat having rectangular recesses in its edges, two plates having inwardly extending rectangular projections 55 entering the recesses in the seat, a rigid trunnion carried by one of the plates and entering the recesses in one stud, a rod passing through the other plate and through the rectangular projections and screw threaded 60 into the rectangular projection of the other plate, a trunnion screwed on the rod on the outside of the plate and entering the recesses of the other stud, the upper ends of the plates having circular projections on their 65 inner faces entering recesses in the cover for pivotally supporting the same.

6. In combination with a toilet, two studs carried thereby, a seat, two plates removably carried by the seat and rigidly connected thereto, an integral trunnion carried by one of the plates, a bolt passing through the seat and screwed into one of the plates, a trunnion screwed on the bolt on the outside of the other plate, and integral studs 70 carried by the upper ends of the plate and entering recesses in the cover for pivotally supporting the same.

In testimony whereof, I have signed this specification.

EDWARD L. DELANY.
